UNITED STATES PATENT OFFICE.

ALBERT H. STEBBINS, OF LOS ANGELES, CALIFORNIA.

CLASSIFIER DECK.

Application filed January 20, 1926. Serial No. 82,408.

This invention relates to a novel deck construction which is adapted primarily to classify materials, but which serves also to some degree as a concentrator deck.

5 Air concentrator tables as constructed heretofore are commonly provided with a deck having a laterally inclined deck surface in which apertures are formed throughout practically the entire surface of the deck, 10 riffles are provided over the deck surface to direct the concentrates or values lengthwise of the deck while the lighter materials or tailings are caused to flow laterally over the side of the deck, and movement is commonly imparted to the deck to advance the 15 materials along its surface.

In operating these concentrator tables of well known construction, in order to secure good results it is necessary to carefully control the strength of the air throughout the deck surface, which requires very careful adjustment of the aperture openings. It is also necessary to carefully regulate the strength and nature of the movement imparted to 25 the deck, and to regulate the feed of the materials and other operating conditions.

The present invention contemplates certain changes in the construction and operation of concentrator decks whereby the materials being treated will be rapidly classified in an extremely satisfactory manner; that is, instead of operating the deck to concentrate materials as heretofore, it is operated to classify the materials. In this 30 manner the classification of materials, which has been effected heretofore in variously constructed air chambers, can be effected in an extremely satisfactory manner upon what may be termed a "classifier deck".

40 The term classification is herein used to designate the separation of different materials into different compartments in accordance with their size and weight, so that materials having a particular size and weight are deposited in one compartment while materials of a slightly different size and weight are placed in the next compartment. In the present case the compartments in which the different size materials are 45 placed are formed by the riffles that divide the deck surface into successive compartments.

In order to make clear the construction and operation of the present "classifier deck" 50 as distinguished from the concentrator decks as usually constructed heretofore, it is

thought advisable to first consider the important feature of the usual concentrator deck.

In the ordinary concentrator deck the 60 strength of the air passing up thru the apertures formed throughout the deck surface is such that the air will lift the small light particles and carry off the dust, but it is not strong enough to disturb the stratifying 65 operation that is taking place over the deck surface under the action of the deck movement. The deck surface is usually inclined transversely so that the lighter materials that are crowded upwardly away from the 70 deck surface by the heavier materials will flow laterally over the riffles, while the heavier materials travel along the riffles toward the concentrate wall.

In accordance with the present invention 75 the deck is constructed and operated so that its primary object is to separate out and promptly dispose of the lighter materials or tailings at the lower side of the deck, and, altho the values or concentrates that remain 80 on the deck surface may be subjected to a concentrating operation, this is of secondary consideration. As a matter of fact two separate and distinct separating operations are carried out upon the deck in accordance with the present invention; that is, in the vicinity of the apertures the air 85 produces a classification both as to size and as to gravity, while as the materials advance further along the deck they undergo a movement separation or classification.

90 One important feature of the present invention resides in a deck surface having apertures formed in only that part of the surface which lies near the material receiving end of the deck, and in the action of the air whereby a classification of the lighter materials or tailings is effected.

95 Another important feature of the invention resides in a deck having a relatively wide band-like portion extending across the deck surface and forming an inclined or up-hill section up which the materials must travel in moving lengthwise of the deck. This construction retards the movement of the tailings lengthwise of the deck and helps to separate them from the concentrates 100 traveling along the deck.

110 This up-hill feature has a further advantage in that it serves to remove most of the fine light particles before the concentrates reach the crest of the hill, and as

a result it is feasible to impart a downhill slope to the remaining portion of the deck; this permits the angle of the riffles relative to the lower side of the deck to be increased, which is desirable as it increases the number of riffles terminating along the concentrate wall.

Still another feature of the invention resides in the construction of the cover extending over the apertured portion of the deck surface whereby the air which is removed from the chamber below this cover is caused to flow transversely of the deck surface to thereby promote movement of the lighter materials toward the lower side of the deck.

Other features of the invention and novel combination of parts in addition to the above will be hereinafter described in connection with the accompanying drawings which illustrate good practical forms of the invention.

In the drawings:—

Fig. 1 is a top plan view of a deck constructed in accordance with the present invention;

Fig. 2 is a side view of the deck of Fig. 1, and of the deck supporting frame;

Fig. 3 is a sectional perspective view of the deck of Fig. 1, but shows the apertures as extending only part way across the deck surface;

Fig. 4 on an enlarged scale is a sectional view taken on the line 4—4 of Fig. 1 and shows the elimination of the values from the tailings as the latter move transversely down the deck surface;

Fig. 5 is a diagrammatic view showing the approximate disposition of the different materials upon the deck surface.

Fig. 6 is a plan view of a modified type of deck;

Fig. 7 is an enlarged sectional view taken on the line 7—7 of Fig. 6;

Fig. 8 is a side view of the deck of Fig. 6;

Fig. 9 is a sectional view taken on the line 9—9 of Fig. 1;

Fig. 10 is a sectional view taken on the line 10—10 of Fig. 1; and

Fig. 11 is a perspective view of a wing to be described.

The configuration of the deck casing forming the subject matter of the present invention may be varied as desired, and the deck shown is elongated in shape and is relatively wide at its material receiving end and tapers to a much narrower width towards its discharge end. The deck casing may be variously constructed and is provided with an air chamber 10 disposed below the deck surface 11 and the materials to be treated are delivered to the deck surface by a hopper 12 mounted at the upper side of the deck and adjacent the left-hand end thereof, viewing Fig. 1. The deck surface

11 is preferably supported so that it slopes in a transverse direction towards the lower or discharge side of the deck, and is provided with a concentrate wall 13 that extends along the upper side of the deck.

The frame for supporting the deck so that it may partake of a back and forth or vibratory movement that will advance the materials over the deck surface may be variously constructed, and the supporting frame, as shown in Fig. 2, is provided with the uprights 14 to which the longitudinally extending rails 15 are secured. The means for mounting the deck upon its frame so that the deck may partake of its vibratory movement may be varied as desired, and in the construction shown the deck is mounted upon a supporting carriage 16 and is preferably secured thereto at its lower side by the hinges 17; this construction is desirable because it permits the transverse inclination of the deck to be varied as desired. In the construction shown the supporting frame is provided near its opposite ends with the transversely extending shafts 18 having the downwardly extending arms 19. These arms are provided with laterally extending stub shafts 20 which are journaled in bearing blocks 21 secured to the under face of the carriage 16, the arrangement being such that as the deck moves back and forth in the direction of its length, it will rise and fall slightly in a well known manner.

Various means might be provided for imparting a back and forth movement to the deck, and the means shown to this end consists of a power operated shaft 22 which is rotatably supported by the machine frame and is provided with an eccentric 23 upon which is mounted the grooved sheave 24. About this sheave is passed a cable 25 one end of which is secured to the carriage frame 16 and the other end is fastened to the machine supporting frame by a bolt 26 provided with adjusting nuts 27. The operating shaft and eccentric just described will serve to move the sheave 24 bodily towards and from the cable tightening position and this will serve to pull the deck in a left-hand direction viewing Fig. 2. The means shown for urging the deck in the opposite direction consists of a cable 28 having one end anchored to the carriage 16, and the opposite end secured to a spring 29, while an intermediate portion of this cable passes about an idle sheave 30. The means just described will serve to move the deck back and forth, and in order that the movement of the deck in a right-hand direction may be suddenly checked to advance the materials lengthwise of the deck, an abutment 31 of any desired construction may be provided, which is secured to the machine frame and is positioned to be engaged by an adjustable bolt or the like 32 carried by the carriage 16.

As above indicated, one of the features of the present invention resides in a deck the deck surface of which has apertures formed only in that portion of its surface which lies 5 near the material receiving end of the deck. The size and shape of the area of the deck surface which is provided with the apertures 33 may be varied as desired, and is shown as having the form of a relatively 10 wide band extending diagonally across the deck from the hopper 12 towards the lower discharge side of the deck. In Fig. 1 these apertures are shown as extending entirely across the deck, whereas in Fig. 3 they are 15 shown as terminating some distance from the lower side of the deck, as indicated by 34. Since only the portion of the deck surface 11 lying near the material receiving end of the deck is provided with apertures, the air 20 chamber 10 need extend under only that portion of the deck surface which is provided with apertures. The air chamber below the deck surface is therefore provided with a partition or wall 35 extending transversely 25 of the deck surface in an inclined direction, and since a small amount of fine material may pass downwardly thru the apertures 33 into the chamber 10 it is desirable to provide means for removing this fine dust-like mate- 30 rial, and the partition 35 is therefore shown as having a portion thereof cut away as at 36 to form an opening thru which the materials may escape from the chamber 10 under the action of the progressive movement im- 35 parted to the deck. Such air as may escape from the chamber 10 thru the opening 36 will be confined in a smaller chamber 37 formed under the deck surface and having the confining walls 38 and 39, and the air 40 may be exhausted from the chamber 37 by a pipe or the like leading from this chamber to suitable exhaust means. The wall 39 may be provided with a small opening 40 through 45 which the materials resting upon the lower floor 41 of the deck may pass towards the discharge spout or opening 42 with which the floor 41 is provided.

It is desirable to form a casing over the apertured portion of the deck surface in 50 order to confine the air and dust rising from the deck surface. The means shown to this end consists of a cover plate 43 which is supported in spaced relation to the deck surface and the air which is confined in the space 55 below the cover 43 may pass upwardly to a hood 44 which communicates with the chamber just mentioned thru the relatively large opening 45 formed in the cover plate 43. The hood 44 may be connected to any suit- 60 able exhaust means not shown for carrying off the air and dust above the deck surface. It should be noted that the opening 45 is disposed at the lower or material discharge side of the deck. This position of the open- 65 ing is highly desirable because it causes the

air in the chamber below the cover 43 to travel transversely of the deck surface in passing towards the exhaust means. This traverse movement of the air helps to carry the lighter particles transversely of the deck 70 towards the discharge side thereof, which is very desirable.

Since the apertures 33 are formed in only a portion of the deck surface, the deck cover 43 extends over only a portion of the deck 75 and as a result air may tend to enter the air chamber below the cover 43 along the edge 46 of this cover, that is, between the edge 46 and the deck surface. To prevent this the apron 47 is provided, which is secured to the 80 under face of the cover 43 adjacent its edge 46 and this apron extends downwardly as close to the deck surface as is practical. As a result of this construction such air as may enter between the lower edge of the apron 85 47 and the deck surface will serve to carry back into the chamber such dust as might tend to escape below the apron 47.

The air passing upwardly thru the apertures formed near the hopper 12 may tend 90 to travel lengthwise of the concentrate wall 13 and escape from under the cover 43 along this wall. To prevent this the wings 48 may be provided which are conveniently secured to the buffer blocks 49, as best shown in Fig. 95 11 and these wings are given sufficient width to extend from the under face of the cover plate 42 downward nearly to the deck surface. The ends of the wings 48 may be curved as at 50 so that they will direct back 100 under the cover the air that might otherwise escape along the concentrate wall, and these wings have a laterally extending flange portion 51 adapted to catch the lighter particles adjacent the wings and to direct these particles back under the cover. 105

The heavier materials or concentrates are directed against the concentrate walls by riffles 52 which are shown in Fig. 6 as extending diagonally over the entire deck surface. These riffles it should be noted are shown in Figs. 1 and 3 as extending diagonally over only the portion of the deck surface which is uncovered, and the riffles 53 lying under the covered portion of the deck 110 surface are shown as extending substantially parallel to the lower side of the deck. This construction is desirable because of the peculiar construction of that portion of the deck surface lying under the cover plate 43 and 115 which will now be described.

As above pointed out one of the important features of the present invention resides in the construction whereby a portion of the deck surface disposed near the material receiving end of the deck is given an up-hill 120 slope, as indicated by 54 whereby the materials traveling lengthwise of the deck are caused to move up this inclined surface. As a result of this construction the materials 125 130

resting upon the deck surface under the cover 43 are subjected not only to the transverse inclination of the deck surface, but also to the up-hill slope 54 which retards the travel of the lighter materials lengthwise of the deck, thus materially increasing the tendency of the lighter materials to separate out from the heavier materials or concentrates before the latter pass over the crest 10 of the hill indicated by 55. As a result of the construction just described, whereby most of the lighter materials and tailings are removed from the concentrates before the latter pass over the crest of the hill, the remaining portion of the deck surface 56 may be given a downward inclination, as best shown in Fig. 3. This will help to advance the materials lengthwise of the deck and permits the use of riffles 52 which may 20 extend diagonally of the deck surface at an increased angle relative to the lower side of the deck; this arrangement being desirable as it increases the number of riffles terminating along the concentrate wall 13. In the operation of the deck forming the subject matter of the present invention it is desirable that the air currents passing upwardly thru the apertures 33 shall be strongest at the upper side of the deck and that these 30 currents shall gradually decrease in strength as the materials pass downwardly towards the lower side of the deck. This variation in the strength of the air currents is readily obtained by varying the size of the opening 35 of the apertures 33, as clearly shown in Fig. 7, wherein it will be noted that the lips 57 of the apertures near the upper side of the deck are bent upwardly to form openings which are much larger than the opening of the apertures near the lower side of the deck. As a result of this construction the strong 40 currents of air passing upwardly thru the materials upon the deck surface near the hopper 12 will quickly lift the lighter materials and tailings so that the heavier particles or concentrates may work downwardly close to the deck surface and these strong air currents will promote a rapid flow of the lighter materials transversely of the deck to 45 wards the lower side thereof. The large heavy concentrates will of course settle between the riffles near the upper side of the deck and will quickly reach the concentrate wall, while the somewhat smaller concentrates will settle between the riffles disposed further down the deck and the lighter particles and tailings will arrange themselves between the riffles lying still further down the laterally inclined deck, thus producing 50 the classifying effect above mentioned. The up-hill portion 54 as previously stated will retard the movement of the lighter materials and tailings lengthwise of the deck and as a result these lighter particles continue 60 to flow transversely along the deck surface over the various riffles and are discharged at the lower side of the deck. The manner in which the concentrates gradually separate out from the tailings as the latter move downward across the inclined deck is clearly indicated in Fig. 4 wherein the concentrates are designated by C and the tailings are designated by T. 70

Due to the up-hill slope given to the portion 54 of the deck it is not feasible to place the riffles extending over this portion of the deck at a transverse inclination to the direction of movement. They are therefore shown as extending substantially parallel to the lower side of the deck, so that they will 75 not unduly retard the movement of the heavier materials lengthwise of the deck. The transverse movement of the air above mentioned may cause some of the finer particles to drop upon the unperforated portion 58 of the deck, in which case the materials will merely travel along the riffles under the action of the deck movement until they reach the apertured portion of the deck. 80 If desired the portion of the deck indicated by 58 may be given a down-hill slope, as shown in the modification of Fig. 8 since this inclination will help advance the materials lengthwise of the deck. 85

Air under pressure may be supplied to the air chamber 10 below the deck surface by the pipe or conduit 59, and in the construction shown in Figs. 1, 2 and 3 employing a deck surface having the up-hill portion 54, the apertures 33 are preferably 90 omitted at the crest 55 of the hill, as the omission of these apertures will tend to slow down the movement of the concentrates lengthwise of the deck. This slowing down of the movement of the concentrates will 105 tend to prevent the tailings from traveling lengthwise of the deck sufficiently to escape from under the cover 43. Since air is exhausted by the means described from the chamber under the cover 43, air from the 110 atmosphere may tend to enter this chamber along the lower side of the deck where the tailings are discharged. In order to prevent air from entering the chamber at this point a canvas apron 60 may be provided 115 the upper edge of which may be secured to the cover 43 so that this flexible apron will hang downwardly over the tailings discharge opening, and a bar 61 secured to the lower edge of this apron will serve as a 120 weight to keep the apron tensioned, while at the same time it will permit the materials discharged from the lower side of the apron to fall between the apron and the side of the deck. 125

Since in the present construction air is forced upwardly thru apertures formed only in a portion of the deck surface a smaller volume of air will suffice to operate the present deck than is required to operate the 130

- type of decks employed heretofore having apertures formed throughout the entire deck surface. This permits a saving in power in supplying air to the deck and also in exhausting it therefrom. Furthermore, since the cover 43 extends over only a portion of the deck the operation of the materials upon the uncovered portion may be readily observed, which is desirable.
- 10 The portion of the concentrate wall 13 lying under the cover 43 may be constructed so that it projects inwardly a substantial distance over the deck surface as at 62. This will produce an accumulation of concentrates 15 against this part of the wall and will help to push the tailings down the inclined deck.
- The modified construction shown in Figs. 7 and 8 is substantially similar in construction and operation to the construction shown in Figs. 1, 2 and 3 except that the deck in this modified construction is not provided with the hump or up-hill portion 54 of Figs. 1, 2 and 3, and as a result the finer materials and tailings will not separate out as quickly in the modified construction as they will in Figs. 1, 2 and 3.
- The condition of the materials being treated upon different portions of the deck shown in the various views of the drawings will be better understood upon reference to the diagrammatic view shown in Fig. 5, wherein dot-and-dash lines extending over the deck surface are provided to outline the approximate area in which the different separating operations occur. The section of the deck shown in Fig. 5 as designated by I is the portion of the deck upon which the small light particles are dropped by the air traveling transversely of the deck surface and which particles are returned to the apertured portion of the deck by the deck movement. The section of the deck indicated by II is that portion in which the air classifying operation takes place and it is this portion of the deck which serves to rapidly separate out the tailings and also the very fine values which it is not practical to treat upon the present machine without materially slowing down the classifying operation. The area designated by III is that section in which a movement classification takes place; that is, the lighter materials which travel along the riffles into this area will reach the concentrates that are lying between these riffles as a result of the cross flow of the concentrates adjacent the concentrate wall. The movement of these lighter materials and tailings against the bank of heavier materials will force the lighter materials up over the top of the riffles to flow transversely of the deck towards the discharge side. The section of the deck designated by IV is that section in which the coarse and fine concentrates collect, as it is
- the area in which the concentrates that are approaching the concentrate wall meet the concentrates that have piled up against the concentrate wall and have fallen away from the same. The narrow section 5 designates 70 the area in which the tailings are almost entirely removed from the concentrates.
- As a result of the deck construction described it will be seen that all waste or light gravity materials under a certain determined size are quickly disposed of by the action of the air which effects their travel across the deck toward the discharge side thereof. At the same time all values or heavy gravity particles of a much smaller size are likewise 80 quickly disposed of at the lower side of the deck. The material remaining on the deck consists of relatively coarse waste and all values except the extremely fine values. These remaining materials may be readily 85 separated by movement alone, thus avoiding the use of air apertures throughout a large portion of the deck.
- What is claimed is:
1. A deck for separating materials, comprising in combination, a deck casing that is supported at a transverse inclination and has a feed hopper at the juncture of the upper side and one end of the deck, a deck surface which is provided with apertures in only that portion of the deck disposed near the feed hopper, said apertures being largest in the vicinity of the feed hopper and decreasing in size downwardly across the deck, riffles extending over the deck surface, means for forcing air upwardly through the apertures to effect a classification of the materials in the vicinity of the feed hopper, and means for vibrating the deck to advance the materials over the deck surface and to effect a movement stratification of the materials as they travel over the unapertured portion of the deck surface.
2. A deck for separating materials, comprising in combination, a deck casing having a feed hopper at one end, a deck surface that is supported at a transverse inclination and which is adapted to effect a classification of the materials near the hopper, and a concentration of the materials throughout the remaining portion of the deck, said surface being provided with apertures only in the portion of the deck near the hopper where the classification of the materials is effected and formed with a hump portion extending transversely of the deck near said hopper to form a hill up which the materials must travel as they move lengthwise of the deck from the classifying portion of the deck to the concentrating portion, riffles extending over the deck surface, and means for operating the deck to advance the materials over its surface.
3. A deck for separating materials, comprising in combination, a deck casing hav-

ing a deck surface that is provided with a hump portion extending transversely of the deck to form a hill up which the materials must travel as they move lengthwise of the 5 deck, riffles extending up the hill portion of the deck and other riffles extending over a different portion of the deck surface and arranged at an angle to the riffles upon the hill portion, and means for operating the 10 deck to advance the materials over the same.

4. A deck for separating materials, comprising in combination, a deck casing having a deck surface that is provided with a hump portion extending transversely of the 15 deck to form a hill up which the materials travel as they move lengthwise of the deck, riffles extending up the hill portion of the deck and arranged substantially parallel to the tailing discharge side of the deck, other 20 riffles extending diagonally over a different portion of the deck surface at an angle to the first mentioned riffles, and means for operating the deck to advance the materials over the same.

5. A deck for classifying materials, comprising in combination, a deck casing provided with a laterally inclined deck surface having apertures formed only in that part of the deck surface that is disposed 30 near the material receiving end of the deck and having a large unapertured portion, means for forcing air thru the apertures with sufficient pressure to promote a rapid movement of the lighter materials trans- 35 versely of the deck toward its discharge side, and riffles for directing the heavier particles lengthwise of the deck and arranged to extend over both the apertured and unapertured portion of the deck.

6. A deck for separating materials, comprising in combination, a deck casing having a deck surface that is provided near the material receiving end of the deck with a wide portion that slopes upwardly to form a hill 45 extending across the deck up which the materials travel as they move lengthwise of the deck and the portion of the deck surface extending from the crest of the hill toward the discharge end of the deck being constructed 50 to slope downwardly to promote travel of the materials toward the discharge end of the deck, riffles upon the deck surface, and means for operating the deck to advance the materials over its surface.

7. A deck for separating materials, comprising in combination, a deck casing having a deck surface that is provided near the material receiving end of the deck with a wide portion that slopes upwardly to form a hill 55 extending across the deck up which the materials travel as they move lengthwise of the deck and the portion of the deck surface extending from the crest of the hill toward the discharge end of the deck being constructed 60 to slope downwardly to promote travel of the

the materials toward the discharge end of the deck, said deck surface having air apertures formed only in the part of its surface that is disposed near the material receiving end of the deck, riffles upon the deck surface, and means for operating the deck to advance the materials over its surface.

8. A deck for separating materials, comprising in combination, a deck casing having a deck surface that is provided near its 75 material receiving end with a wide portion that slopes upwardly to form a hill extending across the deck up which the materials travel as they move lengthwise of the deck and the portion of the deck surface extending from the crest of the hill toward the discharge end of the deck being provided with diagonally disposed riffles and constructed to slope downwardly to promote travel of the materials along the inclined riffles, and 80 means for operating the deck to advance the materials over its surface.

9. A deck for separating materials, comprising in combination, a deck casing having a deck surface that is provided near its 90 material receiving end with a wide portion that slopes upwardly to form a hill extending across the deck up which the materials travel as they move lengthwise of the deck, riffles upon the deck surface, said up-hill portion of the deck surface being provided with apertures to promote separation of the tailings from the values before the latter pass over the crest of the hill, a cover extending over the apertured portion of the deck to form a dust compartment, and means for 95 operating the deck to advance the materials along the same.

10. A deck for separating materials, comprising in combination, a deck casing that is supported at a transverse inclination and has a feed hopper at one end, a deck surface which is provided with apertures in only that portion of the deck disposed near the feed hopper and the apertures being largest near the upper side of the deck and gradually decreasing in size toward the lower side of the deck, a cover extending over the apertured portion of the deck surface to form a dust compartment, and means for exhausting air from the dust compartment at a point near the lower side of the deck to promote movement of the lighter materials with the air toward the lower side of the deck.

11. A deck for separating materials, comprising in combination, a deck casing having an apertured deck surface, riffles upon the deck surface, a cover extending over only the portion of the deck surface that is adjacent the material receiving end of the deck, means for exhausting air from the dust chamber under the cover, and an apron extending downwardly from the end portion of the cover into close proximity to the deck surface to prevent air from entering the

dust chamber at points between the end of the cover and the deck surface.

12. A deck for separating materials, comprising in combination, a deck casing having an apertured deck surface, riffles upon the deck surface, a concentrate wall extending along one side of the deck, a cover extending over only the portion of the deck surface that is adjacent the material receiving end of the deck and said apertures being formed only in that portion of the deck surface that lies below the cover, means for forcing air upwardly thru the apertures, and a wing disposed along the concentrate wall under the cover and constructed to direct back under the cover the air currents that tend to pass out from under the cover along the concentrate wall.

13. A deck for separating materials, comprising in combination, a deck casing having an apertured deck surface, riffles upon the deck surface, a cover extending over the deck surface, a concentrate wall extending along one side of the deck and having a portion near the material receiving end of the deck that projects inwardly a substantial distance over the deck surface to produce an accumulation of concentrates near said end of the deck, and means for actuating the deck to advance the materials over its surface.

14. A deck for separating materials, comprising in combination, a deck casing having an apertured deck surface but having the apertures omitted from a portion of its surface lying at the discharge side of the deck near its material receiving end, a cover extending over the deck surface and provided with means for withdrawing air from the dust compartment below the cover at a point above said unapertured portion of the deck, and riffles upon the unapertured portion of the deck for directing toward the apertures the materials that settle out of the air upon the unapertured section.

15. A deck for separating materials, comprising in combination, a deck casing that has a feed hopper at one end, an apertured deck surface that is supported at a transverse inclination and which has an upwardly inclined portion extending across the deck surface near the feed hopper and up which the materials must travel as they move lengthwise of the deck, riffles extending over the deck surface, a cover mounted over the deck surface to form a dust compartment, and means for exhausting air from the dust compartment at a point near the lower side of the deck to promote movement of the lighter

materials with the air toward the lower side of the deck.

60

16. A deck for separating materials, comprising in combination, a deck casing having a transversely inclined deck surface, riffles extending over the deck surface, and the deck surface having an apertured section in the form of a wide band extending diagonally across the deck surface from the material receiving portion of the deck to the tailing discharge side of the deck and having the apertures omitted from the other portions of the deck surface.

65

17. A deck for separating materials, comprising in combination, a deck casing having a transversely inclined deck surface and having near the material receiving end of the deck a wide band-like portion of the surface that extends diagonally across the deck from the upper side of the deck to the tailing discharge side and disposed to form a hill up which the materials must travel as they move lengthwise of the deck, and riffles extending over the hill portion of the deck surface and also over a large area of deck surface lying between the said hill portion and the delivery end of the deck.

75

18. A deck for separating materials, comprising in combination, a deck casing having a transversely inclined deck surface and having a wide band-like portion of the surface that extends diagonally across the deck from the material receiving portion thereof to the tailing discharge side of the deck and disposed to form a hill up which the materials must travel as they move lengthwise of the deck, said deck surface having apertures formed only in the vicinity of its wide band-like portion, and riffles extending over the deck surface.

80

19. A deck for separating materials, comprising in combination, a deck casing having a deck surface that is provided with an upwardly inclined portion forming a hill extending transversely of the deck and up which the materials travel as they move longitudinally of the deck, said deck having apertures formed in the portion of the deck surface that constitutes the side of the hill but omitted from the crest of the hill to slow down the movement of the materials at the top of the hill, riffles upon the deck surface, and means for operating the deck to advance the materials over the same.

100

In testimony whereof, I have signed my name to this specification.

ALBERT H. STEBBINS.
